UNITED STATES PATENT OFFICE.

GEORGE S. CLAUER, OF SOUTH AMBOY, NEW JERSEY.

CAR-BRAKE.

1,178,781.

Specification of Letters Patent.

Patented Apr. 11, 1916.

Application filed October 26, 1915. Serial No. 57,974.

To all whom it may concern:

Be it known that I, GEORGE S. CLAUER, a citizen of the United States, residing at South Amboy, in the county of Middlesex and State of New Jersey, have invented new and useful Improvements in Car-Brakes, of which the following is a specification.

This invention relates to improvements in devices for causing the positive stoppage of vehicles, with special reference to types running on track rails, where it is often desirable to cause the car to come to an instant halt, in order to prevent damage and injury to persons or things in its pathway.

15 The principal object of the invention is to provide a device whereby the results, as stated above, are effectually performed without special manual exertion on part of the operator.

20 Other objects are to provide such stopping means in forms that can be installed on cars as presently constructed, either when in the process of manufacture or at a later period.

These objects are attained by the novel 25 construction and combination of parts hereafter described and shown in the accompanying drawings, forming a material part of this specification, and in which:

Figure 1 is a side elevation of a common 30 type of street car showing the application of the invention. Fig. 2 is an enlarged fragmental side view, showing in detail the construction of the brake, and drawn to an enlarged scale. Fig. 3 is a partial sectional 35 and end view, taken on line 3—3 of Fig. 2. Fig. 4 is plan and sectional view, drawn to a further enlarged scale, of a part of the braking mechanism and taken substantially on line 4—4 of Fig. 5. Fig. 5 is a partial front 40 and sectional view of the same, the section being taken on line 5—5 of Fig. 4. Fig. 6 is a sectional view of a track rail and brake shoe, used with the device, the section being taken on line 6—6 of Fig. 7. Fig. 7 is a 45 partial side view of the same. Fig. 8 is a plan view of the contacting elements of the brake, indicating their normal position with reference to the rails, and Fig. 9 is a perspective detail, showing the means by which 50 the brake is attached to the car.

Referring to the drawings, and more particularly to Fig. 1 thereof, an ordinary type of car is indicated by the numeral 15, which may be driven by any of the usual means as 55 steam, compressed air, electricity, etc., and

provided with a cylinder 16, adapted to receive compressed air from any convenient source supplied by the motive power of the car.

A heavy steel plate 18 is rigidly secured 60 below the car body, extending from end to end thereof, and to this plate is attached a cylinder 19, by means of the flange 20, transverse openings 21 being formed in the flange and also partially through the cylinder 19, 65 the openings acting as a guide-way for the rod 23, having an enlarged portion 24, the upper and lower sides 25 of which are formed with inclined surfaces in the manner of a wedge. The rod 23 may be connected 70 operatively with a piston movable in the cylinder 16 or moved in any other preferred manner.

The cylinder 19 has formed transversely through its walls at right angles to the 75 opening 21, elongated slots 26, opposite to each other, and movable freely therein, is a pivot bar 27 held normally upward by reason of the coiled pull springs 28, secured at their upper ends to eyes 29, set in the plate 80 18, the lower ends being connected with rings 30, surrounding the bars 27 and held in place by collars 31.

Centrally between these collars, on the bars 27, are the rod ends 33 engaging with 85 the rods 35 which pass down into the cylinder 36 through the cover 37 attached thereto, and terminating in a flanged disk or collar 38 which is rigidly connected with the rod 35 by means of the hub 39.

The cylinder 36 has an integrally formed 90 head, 40 provided with an extension 41, in which is secured the stub end of a rod 42, terminating at its lower opposite end in the tenon 44, pivotally engaged with the brake 95 carriers 45, to which are removably attached the brake shoes 46, which make contact with the rails as indicated.

Connecting between the brake carriers are 100 bars 47 by which the braking elements are held in relative rigid position, forming in effect the base of a triangle to which the bar 27 is the apex.

Interposed between the flange 38 and bottom 105 of the cylinder 36 are a plurality of springs 48 adapted to exert pressure therebetween so that the brake shoes may not make too rigid contact with the rails when the bar 23 is actuated by the admission of air to the cylinder 16, whereby the bar 27, 110

with its attached parts, are moved down, causing the brake shoes to impinge upon the track rails and effect stoppage of the car.

When the rod 23 is moved in the opposite direction, the springs 28 draw the bar 27 upward allowing the car to proceed.

Thus it will be seen that an effective device is provided which will bring the car to a stop by the combined effects of its own weight applied through the wedge 24, but materially eased by the action of the springs 48 so as to avoid any violent shock which would otherwise take place.

While I have shown and described a preferred embodiment of the brake apparatus, it is to be understood that modifications may be made therein relative to the scope of the appended claims.

What I claim as new and desire to obtain by Letters Patent is:—

1. In a braking device for railway cars, pairs of spaced brake elements adapted to make frictional contact with the track rails on each side of the car, connections between the elements in each pair whereby they are

held in rigid relation, other connections converging to a common central pivot, a vertically slideable head in which the pivot is mounted, means for actuating said head, and means combined with said connections whereby said elements are tensionally applied to the rails when said head is depressed.

2. In a vehicle adapted to operate upon a track-way, the combination with a power source, of a rod operable thereby, a plate secured at the bottom of the vehicle, a bracket on said plate, said bracket acting as a supporting guide for said rod, a pair of rods pivotally and slidably engaged in said bracket, said rods being divergently mounted, brake shoes at the ends of said rods, means combined with the first named rod for depressing said second rods, and a resilient connecting means interposed between said second named rods and said brake shoes.

In testimony whereof I have signed my name to this specification.

GEORGE S. CLAUER.
